UNITED STATES PATENT OFFICE

1,988,191

MARBLE SHOOTER

Peter Donato, Patchogue, N. Y.

Application May 2, 1934, Serial No. 723,605

3 Claims. (Cl. 273—129)

The present invention relates to new and useful improvements in marble shooters, and has for one of its important objects to provide, in a manner as hereinafter set forth, a device of this character embodying novel means for retaining a marble.

Another important object of the invention is to provide a marble shooter comprising novel means for mounting said shooter on the hand in a manner to permit the device to be conveniently and accurately aimed.

Other objects of the invention are to provide a marble shooter which will be comparatively simple in construction, strong, durable, compact, light in weight and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in side elevation, showing a marble shooter constructed in accordance with the present invention in use.

Figure 2 is a view in vertical longitudinal section through the invention.

Figure 3 is a view in vertical longitudinal section through the forward end portion of the shooter, showing the plunger in its projected or inoperative position.

Figure 4 is a view in vertical transverse section, taken substantially on the line 4—4 of Figure 2.

Figure 5 is a detail view in perspective of the marble retainer.

Referring now to the drawing in detail, it will be seen that the embodiment of the invention which is illustrated comprises a barrel 1 of suitable material, said barrel being open at its forward end, as at 2, and being closed at its rear end by a closure disk 3. Fixed beneath and intermediate portion of the barrel 1 is a saddle 4 having downturned end portions 5 to which the ends of a substantially U-shaped bale or handle 6 are pivotally connected, as illustrated to advantage in Figure 4 of the drawing. Fixed to an intermediate portion of the saddle 4 is a dependent finger receiving ring 7.

The reference numeral 8 designates a plunger which is mounted for rotation in the barrel 1 and which is provided with a socket 9 for the reception of a marble which is designated by the reference numeral 10. The plunger 8 is fixed on the

forward end of a stem 11 which passes slidably through the closure 3 and has fixed on its outer end a knob or handle 12.

The reference numeral 13 designates generally a marble retainer. The retainer 13 includes a cross head 14 which is slidably mounted on the stem 11 and from which forwardly projecting resilient fingers 15 extend. The fingers 15 are slidably engaged in passages 16 which are provided therefor in the plunger 8, said passages 16 extending from the rear end of the plunger toward the forward end thereof and terminating in inwardly curved forward end portions which communicate with the socket 9, as best seen in Figure 3 of the drawing.

The retainer 13 and plunger 8 are yieldingly urged forwardly in the barrel 1 by a coil spring 17 which encircles the stem 11 and which has one end engaged with the closure 3 and its other end engaged with the cross head 14. The retainer 13 is yieldingly urged toward inoperative or retracted position by a comparatively weak coil spring 18 which encircles the stem 11 and which has one end engaged with the plunger 8 and its other end engaged with the cross head 14.

The plunger 8 is normally in the position shown in Figure 3 of the drawing. In use, a finger is slipped into the ring 7 for mounting the barrel 1 on top of said one finger in parallelism therewith, as suggested in Figure 1 of the drawing. The handle 6 is then gripped in the palm of the hand and the shooter may now be accurately aimed. The discharge end of the barrel 1 is then elevated slightly and the marble 10 is placed in the socket 9. The knob 12 is then utilized for retracting the plunger 8 against the tension of the coil spring 17. As the plunger 8 is retracted the coil spring 17 is compressed and forces the retainer 13 forwardly against the tension of the comparatively weak spring 18, thus projecting the fingers 15 into the socket 9 for retaining the marble 10 therein, as clearly shown in Figure 2 of the drawing. The plunger 8 is then released and is moved forwardly by the spring 17 for ejecting the marble, as is believed to be readily apparent. As the plunger 8 moves forwardly the spring 18 moves the cross head 14 rearwardly on the stem 11 thereby withdrawing the resilient fingers 15 from the socket 9 for releasing the marble.

It is believed that the many advantages of a marble shooter constructed in accordance with the present invention will be readily understood, and although a preferred embodiment of the invention is as illustrated and described, it is to

be understood that changes in the details of construction and in the combination and arrangement of parts may be resorted to which will fall within the scope of the invention as claimed.

Having thus described my invention, what I claim as new is:

1. A marble shooter of the class described comprising a barrel, a stem extending slidably into the barrel, a plunger fixed on the stem and operable in the barrel, said plunger having a socket therein for the reception of the marble, a cross head slidably mounted on the stem, resilient fingers mounted on the cross head and extending slidably into the socket for releasably securing the marble therein, a coil spring yieldingly urging the plunger and the fingers forwardly, and a weak spring, weaker than said spring, on the stem between the head and the plunger yieldingly urging the fingers toward retracted position.

2. A marble shooter of the class described comprising a barrel, a stem extending slidably into the barrel through the rear end thereof, a handle on the rear end portion of the stem, a plunger fixed on the forward end portion of the stem and operable in the barrel, said plunger having a socket therein for the reception of the marble

and further having passages therein communicating with the socket, a cross head slidably mounted on the stem, resilient fingers mounted on the cross head and extending slidably into the passages for engagement in the socket for releasably securing the marble therein when the plunger is retracted, a coil spring encircling the stem and engaged with the cross head for yieldingly urging the retaining fingers toward operative position and for yieldingly urging the plunger forwardly in the barrel, and a weak coil spring, weaker than said spring, encircling the stem between the head and the plunger and engaged with the cross head for retracting the marble retaining fingers when the plunger is moved forwardly in the barrel by the first named coil spring.

3. A marble shooter of the class described comprising a barrel, a plunger operable in the barrel, and means for mounting the barrel on the hand, said means including a saddle fixed beneath an intermediate portion of the barrel and including downturned end portions, a substantially U-shaped handle pivotally connected, at its ends, to said downturned end portions, and a depending ring for the reception of a finger, fixed to an intermediate portion of the saddle.

PETER DONATO.
